UNITED STATES PATENT OFFICE

EDMUND C. MORGAN, DECEASED, LATE OF NEW YORK, N. Y., BY OLIVE EUGENIE MORGAN, EXECUTRIX, OF NEW YORK, N. Y.

FLUID PRESSURE BREAKING MECHANISM FOR MINING MACHINES

Application filed June 12, 1929. Serial No. 370,431.

The invention relates to apparatus operated by fluid pressure to dislodge material in a mine and is particularly adapted for use in mining machines for mining coal.

5 One of the objects of the invention is the provision of an improved and efficient expandible breaking device adapted to be inserted in a kerf in a mine vein and operated by fluid pressure to dislodge material from 10 the unmined mass.

A further object of the invention is the provision of interior self-restoring mechanism for an expandible fluid pressure operated breaking device.

15 A further object of the invention is the provision of apparatus for exerting fluid pressure suddenly on the expandible breaking device adapted to be inserted into an incision in a mine wall.

20 A further object is the provision of improved and efficient automatic controlling mechanism for a hydraulically operated expandible breaker adapted to be inserted in a kerf in a mine wall.

25 A still further object of the invention is the provision of a plurality of breaking devices independently connected to separate impulse producing devices.

Other objects of the invention will appear 30 hereinafter, the novel features and combinations being set forth in the appended claims.

Referring to the accompanying drawings:

Fig. 1 is a sectional elevational view illustrating the automatically controlled hydraulic mechanism for transmitting pressure to 35 hydraulic breaking devices;

Fig. 2 is an elevational view of an upright kerf-cutter showing the application of hydraulic breakers to a mining machine for operation in a kerf produced by such mining machine;

Fig. 3 is a plan view partly in horizontal section of a plurality of hydraulic impulse producing devices;

40 Fig. 4 is a sectional view on the line 4—4 of Fig. 3, looking in the direction of the arrows;

Fig. 5 is a sectional view of Fig. 3 on the line 5—5, looking in the direction of the 45 arrows;

Fig. 6 is a sectional elevation taken through the center of the upper hydraulic breaker shown in Fig. 2;

Fig. 7 is a sectional view of Fig. 6 on the line a—a looking in the direction of the arrow 2;

Fig. 8 is a sectional view on the line a—a of Fig. 6, looking in the direction of the arrow 3;

Fig. 9 is an elevational view of a modification of the removable plunger of Fig. 6;

Fig. 10 is a sectional elevation on the line 10—10 of Fig. 9;

Fig. 11 illustrates a modification of the structure shown in Fig. 6; and

Fig. 12 is a diagrammatic view in sectional elevation of a modification of the valve structure shown at the right-hand portion of Fig. 1.

Referring to Figs. 6, 7 and 8, which show the type of hydraulic breaker particularly adapted for use in connection with kerf-cutters in mining machines as shown in Fig. 2, it will be seen that this breaker comprises two principal elements relatively expandible. One of these elements is in the form of a shallow cup as shown at 13 in Fig. 6. The other element 14 is in the form of a disc adapted to fit in the cylindrical recess 15 of the casing 13. The disc 14 is movable axially relatively to the casing 13 and therefore in effect constitutes a plunger which is expandible to the dotted line position shown in Fig. 6, assuming that 17 designates the solid portion of the unmined mass of coal and 18 designates the material between the kerf 19 and a kerf distant therefrom toward the left as viewed in Fig. 6.

The shallow cylinder 13 as well as the plunger 14 are relatively thick and of material to give them considerable strength for action in a hydraulic breaker of the expandible type. The cylinder 13 may be rigidly secured to the kerf-cutter frame 20 shown in Fig. 2, or the cylinder 13 may be inserted through a circular opening in the kerf-cutter frame 20 so as to leave an annular space 21 between the frame 20 and the cylinder 13, as shown in Fig. 6. In that event the pipe 22 extending through a strap 23, as shown in Fig. 2, may be relied upon to support the

hydraulic breaker in proper position in the circular opening in the kerf-cutter frame 20.

The pipe 22 may also be secured by an additional strap 24 to the kerf-cutter frame 20, as shown in Fig. 2. Preferably the pipe 22 passes by the cutter-chain 25 on the inside or distant from the solid mine wall 17 shown in Fig. 6. This is effected by extending the pipe 22 through an opening 26 in the kerf-cutter frame 20. In a similar manner an additional hydraulic breaker 13', 14' may be mounted at the lower portion of the kerf-cutter frame 20, as shown in dotted lines in Fig. 2. The pipe 22' is extended through a bracket 23' and thence through an opening represented by the oval dotted line 27, in order that the pipe may be secured by the strap 28 to the inside surface of the frame 20.

The type of hydraulic breaking mechanism 20 shown in Figs. 2, 6, 7 and 8 is particularly applicable to the two upright spaced-apart side kerf-cutters shown in the Edmund C. Morgan Patent No. 1,116,356, granted November 3, 1914, for coal mining apparatus.

25 It should be understood that one or more of such hydraulic breakers may be mounted upon each of the upright frames of the respective spaced-apart kerf-cutters within the boundaries or path of travel of the chain-cutters, as shown in Fig. 2 of the drawings in the present application.

When fluid pressure is exerted through the passage 29 the plunger 14, shown in Fig. 6, may be forcibly moved out to the dotted line position 16 while the cylinder 13 rests firmly against the unmined mass 17, thereby effecting the breaking down of the coal 18. Therefore, when spaced-apart upright kerf-cutters are provided with such hydraulic 40 breaking devices such as that shown in Fig. 6 the plungers 14 should face toward each other so that the opposite breaking devices will move toward each other to break down the material between the kerfs.

45 In order to limit the outward movement of the plunger 14 I have provided a key 30 secured to the cylinder 13 by means of the screw 31. The key 30 fits into a slot 32 on the periphery of the plunger 14 parallel to the 50 axis of the latter. This slot 32 terminates short of the inner surface of the plunger 14 so as to leave an abutment 33 to engage the key 30 and thus limit the outward movement of the plunger 14 relatively to the cylinder 13.

55 By means of the ring 34 fitting in an annular recess 35, an annular packing 36 angular in cross-section may be secured on an annular seat by means of the bolts 37 screw-threaded into the plunger 14. The packing 60 36 is therefore in the nature of a piston packing to prevent leakage of the fluid pressure medium from the chamber within the cylinder 13.

It should be noted that Fig. 7 is a section 65 taken on the line *a*—*a* of Fig. 6, looking in

the direction of the arrow 2, the parallel dotted lines adjacent the section line indicating the hidden edges of the circular opening in the plate 20. Fig. 8 is a section of Fig. 6 on the line *a*—*a*, looking in the direction 70 of the arrow 3. It should be noted that the annular portion 39 is the annular seat on the plunger 14 against which the annular packing 36 rests when secured in position. It should also be noted that the ring 34 is provided with a cylindrical portion 40 in position to contact with the bottom 41 of the cup-shaped recess or opening in the frame 13.

The opposite end of the spring 42 is provided with a diametrical extension or latch 75 80 85 90 95 100 105 110 115 120 125 130 135 140 145 150 155 160 165 170 175 180 185 190 195 200 205 210 215 220 tive to the key itself enables the operator to readily determine when the spring extension or latch 47 is in proper position to enter the slot 57, and after the slot 32 has been turned to receive the key 30, the latter will lock the extension 47 against turning movement relatively to the keepers 51 and 52. It will thus be seen that the key 30 and the slot 32 not only form limit stop mechanism for the plunger 14 but also lock the plunger 14 in the position where the extension 47 is under the offsets 51 and 52 as shown in Fig. 8. The spring is effectively and entirely enclosed in a very compact manner within the space which receives the pressure medium and therefore the operation of the spring is not interfered with by coal dust or other extraneous material. The spring acts automatically to restore the plunger to its initial position when the pressure medium is withdrawn and therefore the fluid pressure breaker will always be in readiness whenever desired for insertion into a comparatively narrow kerf. This arrangement assures continuous forward movement of the mining machine since the latter does not have to be withdrawn for manual restoration of the relatively movable parts of the breaker. In other words, by providing the spring on the interior of the breaker, the latter may be located within the boundaries of the chain kerf-cutter and intermittently operated while the mining machine is continuing its forward feeding movements.

Moreover, whenever desired, for repair, cleaning or otherwise, the key 30 may be removed and the plunger 14 turned anti-clockwise to release the same from the spring 42 so that such plunger may be withdrawn from the cylinder 13.

Fig. 11 shows a modification of the structure shown in Fig. 6 in that the dimensions are smaller with respect to the diameters and the spring may be released or secured in position by the turning of exposed nuts. The pressure pipe 22 is connected to the cylinder 65 so as to communicate with the interior of chamber 66 which is provided with a cup-shaped or cylindrical recess 67 in which fits the plunger or piston 68 having an annular packing 69 secured to the inner end thereof by means of screws 70 and 71. A strong spring 72 fits in a cylindrical chamber 73, the convolutions of the spring being in contact with each other so that this spring may act as an expansion spring to restore the plunger 68 to its initial position when the pressure medium in the chamber 66 is withdrawn. One end of the spring 72 is screw-threaded at 74 to receive a nut 75 which is located in a recess in the outer surface of the plunger 68. It will be seen that the screw-threaded end 74 of the spring 72 passes through the center of the outer portion of the plunger 68.

The other screw-threaded end 76 of the

spring 72 passes through the center of the bottom of the cylinder 65 and receives a nut 77 in the recess 78. A conically-shaped projection or spear-head 79 may be screw-threaded at 80 into the recess in which the nut 75 is located. This conical projection may be added to the plunger 68 when desired to form a pointed instrument or spear-head for penetrating the kerf cut material such as that shown at 18 in Fig. 6 while the bottom of the cylinder 65 rests against the solid unmined mass such as that shown at 17 in Fig. 6.

Such a pointed instrument 79 will assist in initially splitting the material thus assisting in breaking it down and dislodging it from the unmined mass between the spaced-apart upright side kerf-cutters and above the undercutting kerf-cutters.

Referring now to Fig. 1, the apparatus for producing fluid pressure in such hydraulic breakers as those shown in Figs. 6 and 11 will be described. Mounted on the stationary frame 81 is a hydraulic cylinder 82 along which is longitudinally movable a plunger 83 for forcing the pressure medium 84 into the pipe 22 and thence to the hydraulic breakers.

An electric motor 85 is connected by means of gearing 86 to the hydraulic pump 87. By means of this pump the liquid is pumped from the tank 88 through the pipe 89 into the pipe 90 and thence into the cylinder 82. From the cylinder 82 the liquid is passed through the pipe 91 into the pipe 22 when the valve 92 is in the position shown in Fig. 1. By means of this electrically operated hydraulic pump, pressure may be exerted through the pipe 22 into the hydraulic breaker to move the plunger thereof relatively to the cylinder against the action of the expansion spring within the breaker. This operation is comparatively slow, however, and therefore additional mechanism has been provided for securing comparatively quick action of the plungers and thereby effect hammer-blows of said plungers on the material to be broken down. When the breaker is operated by means of the pump mechanism alone it may be automatically restored to initial position by turning the valve 92 so that the pipe 22 will communicate through the valve 92 to the tank 88.

The spring within the breaker will then restore the plunger to initial position and cause the pressure medium therein to flow back through the pipe 22 into the tank 88. The latter may be provided with a screw-threaded cap 93 to close a filling opening.

The apparatus for producing the hammer-blown action comprises a large cylinder 94 in which fits a piston 95 connected to a piston rod 96 coupled at 97 to the plunger 83. A spring 98 is located between one end of the air pressure cylinder 94 and the piston 95 back of the latter. This spring tends to force the piston 95 and the plunger 83 toward the left but when the electric motor 99 operates

the gearing 100, the air pump 101 will force air under compression into the cylinder 94, thereby moving the piston 95 toward the right against the action of the spring 98 until the collar 102 secured to the piston rod 96 engages the lever 103 and swings the latter on its pivot 104 at the upper end of the bracket 105 which is mounted on the frame 106.

Swinging of the lever 103 to the right will cause its arm 107 to transmit upward movement to the spring 108 to lift the switch lever 109 and close the switch 110. Closing of the switch 110 will connect the positive and negative mains through the electro-magnet 111 and the motor 85. The electro-magnet 111 will retain the switch 110 in closed position even after the electric motor 85 has operated the hydraulic pump 87 sufficiently to cause the plunger 83 to move to the left and the collar 102 to move away from the lever 103.

When, however, the plunger 83 has moved to the left sufficiently to cause the coupling 97 to engage the lever 103 its upper curved extension 112 will engage the top of the lever 109 and thereby automatically and forcibly open the switch 110 and cut off the current from the electric motor 85 and thus automatically stop the operation of the pump 87.

The motor for the air pump is also automatically controlled. Whenever the air pressure in the cylinder 94 is sufficient to hold the piston 95 to the right, as shown in Fig. 1, the air pressure exerted through the pipe 113 into the auxiliary cylinder 114 will move the piston 115 and piston rod 116 to the right against the action of the spring 117. The piston rod 116 is pivoted at its right-hand end to the lever 118 which is pivoted at 119 to the frame 81. Also pivoted at 119 for movement relatively to the lever 118 is a switch lever 120 which is connected by a spring 121 to an arm 122 extending from the lever 118.

When the pressure within the cylinder 94 falls below a predetermined amount, particularly when the coupling 97 engages the lever 103, the spring 117 will move the switch lever 120 to the dotted line position and thereby cause the closure of the switch 123. The electro-magnet 124 will then be energized to hold the switch 123 in closed position and the circuit through the motor 99 will be closed to cause the operation of the air pump 101. When the air pressure in the cylinder 114 is sufficient to move the piston 115 to the right a sufficient distance to cause the finger 125 to engage the switch lever 120 and move the latter to the left, the switch 123 will be automatically opened and the current automatically cut off from the motor 99 to effect an automatic stopping of the operation of the air pump 101.

From the foregoing it will be seen that considerable air pressure may always be

maintained on the piston 95 tending to move the plunger 83 to the right. Therefore, whenever the valve 92 is opened to establish communication between the cylinder 82 and the pipe 22, the air pressure accumulator will act very quickly to cause the flow of the liquid from the cylinder 82 through the pipe 22 into the hydraulic breaker whether the pump 87 is operating at such time or not. When the valve 92 is opened and said hammer-blow on the hydraulic breaker is effected, the plunger 83 will move to the right. When the plunger 83 has been moved to the right to the position shown in Fig. 1, the switch 110 will be closed and the motor 85 automatically started to operate the pump 87 and produce sufficient pressure in the cylinder 82 to again move the plunger 83 to the left, until the coupling 97 effects the opening of the switch 110 and the stopping of the motor 85 which in turn stops the pump 87. It will thus be seen that while the hydraulic pump supplies the pressure on the liquid in the cylinder 82 the quick initial operation of the hydraulic breaker depends primarily on the air pressure accumulator. The apparatus therefore operates automatically to effect a quick hammer-blow initially which may be supplemented automatically by the operation of the pump when the plunger 83 moves a sufficient distance to the right, as viewed in Fig. 1.

The greater the number of times that the hydraulic breakers are operated, the more often must the hydraulic pump 87 be automatically operated to restore the pressure in the cylinder 82. During normal operation the piston 95 may occupy a position intermediate the ends of the cylinder 94 where the collar 102 and coupling 97 will be equally spaced from the lever 103. After the hydraulic breakers have been operated a number of times the collar 102 will engage the lever 103 to effect the starting of the pump 87 and when pressure has been restored sufficiently in the cylinder 82 the coupling 97 will engage the lever 103 and cut off the current from motor 85. After this occurs the hydraulic breakers may still be operated by the air pressure accumulator until there has been sufficient flow of the pressure medium 84 from the cylinder 82 to cause the collar 102 to engage the lever 103 and close the switch 110. The entire system is automatic and under the control of an operator who merely manipulates the valve 92.

It should be noted that when desired the hydrostatic expandible device shown in Fig. 6 may be operated so as to be expanded to a limited extent where the bottom of the cylinder 13 and the outer face of the plunger 14 will engage the walls 17 and 18 of the kerf and slide along the same during the feeding operation of the kerf-cutter shown in Fig. 2. After the expandible structure shown in

Fig. 6 has been expanded to a limited extent so as to act as a spacer it may be locked in such position by closing the valve 92 against any ingress or egress of water from the pipe 22. As the feeding operation continues and the expansible device slides along the walls of the kerf, the kerf is kept open by preventing the walls 17 and 18 from moving toward each other and thereby binding of the kerf-cutter 22 in the kerf is prevented and free feeding movement of such kerf-cutter is facilitated. Whenever desired the valve 92 may be operated to secure the breaking down operations hereinbefore mentioned.

In Fig. 12 is shown a modification of the valve 92 of Fig. 1. The full line position of the valve 92' is obtained when the lever for operating this valve occupies the position indicated by the dotted line 126. Communication will then be established between the pipes 91 and 22. When the operating lever is in the position indicated by the dot-and-dash line 127, communication will be established between the pipes 91 and 128 and also 25 between the pipes 22 and 128. When the operating lever is in the position of the dot-and-dash line 129 communication will be established between the pipes 22 and 128. By means of the valve thus arranged, communication may first be established between the pipe 91 and pipe 22 to a hydraulic breaker to fill the same entirely with the pressure medium such as water. Now, if the lever is turned to the position shown at 127 the 30 plunger 83 will tend to move rapidly toward the right and then if the lever is turned back to the position 126 the continued movement of the plunger 83 will cause a hammer-blow to be exerted on the plunger of the hydraulic breaker. When the operating lever is turned to the position shown at 129 the breaker will be automatically restored to initial position. It should also be noted that the operating lever may be turned to establish communication 40 between the pipes 91 and 22 and then quickly moved to the position shown at 129 to establish communication between the pipe 22 and the pipe 128. Furthermore, whenever it is desired to effect the operation of 45 the pump 87, the position 127 could be effected so that the plunger 83 would move to the right until the lever 103 closes the switch 110 and starts the motor 85.

In Figs. 3, 4, and 5, is shown a modification 55 of the structure shown in Fig. 1, in that separate cylinders 130 and 131 are provided instead of the single cylinder 82 of Fig. 1. In this manner independent control of the pressure medium through the pipes 22 and 22' leading to hydraulic breakers is obtained, one located on one upright side kerf-cutter and the other located on another upright side kerf-cutter, the kerf-cutters being spaced apart.

As shown in Fig. 3 the piston rod 96' is

connected by a coupling 97' to two spaced-apart plungers 132, 133, respectively movable in the cylinders 130 and 131, which are located in a casting 134 secured to the frame 70 131'. Leading downwardly from the right-hand end portions of the cylinders 130 and 131 are pipes 135 and 136 in which valves 137 and 138 are located, these valves being similar to that designated 92 in Fig. 1, which are separately and independently controllable by means of the levers 139 and 140.

There are two pumps 141 and 142 each similar to that designated 87, and both connected to be operated simultaneously by the power transmission mechanism 86 shown in Fig. 1. Pipes 143 and 144 lead upwardly from these pumps to the cylinders 130 and 131 in the same manner that the pipe 90 leads upwardly from the cylinder 82 in Fig. 1. This may be seen by referring to Fig. 4 which is a sectional elevation of Fig. 3 on the line 4-4, looking in the direction of the arrows. Fig. 5 is a sectional elevation of Fig. 3 looking in the direction of the arrows or from right and left.

It should also be understood that the kerf-cutter shown in Fig. 2 may be mounted on a long wall machine or on any other type of kerf-cutter making a kerf spaced back from the face of the mine wall so that a hydraulic breaker mounted on the frame of the kerf-cutter may act to exert pressure toward the free face to dislodge coal from the unmined mass. In other words, the breaking mechanism herein disclosed is adapted to be mounted on a kerf-cutter which forms a kerf in a mine wall spaced from the free face or working face of the coal. The breaking mechanism will then constitute hydrostatically actuated means carried by the kerf-cutter to exert pressure toward such free face to dislodge the coal.

Obviously those skilled in the art may make various changes in the details and arrangements of parts herein disclosed without departing from the spirit and scope of the invention as defined by the claims hereto appended and it is wished therefore not to be restricted to the precise construction herein disclosed.

Having thus fully disclosed an embodiment of the invention, what is desired to be secured by Letters Patent of the United States is:

1. In a breaking device, the combination with a cylinder, of a spring adapted to be located within said cylinder, means for securing one end of said spring to the bottom of said cylinder, a plunger movable in said cylinder, and latch mechanism between the inner side of said plunger and the other end of said spring for detachably securing said plunger to said spring.

2. A breaking device adapted to be inserted in a kerf in a mine wall and comprising

- ing a cylinder and a plunger, an enclosed spring having one end connected to the cylinder and the other end detachably connected to said plunger, means on the plunger adapted to receive a turning tool to connect said plunger to said spring, and means for locking said plunger against turning relatively to said cylinder after said plunger is connected to said spring.
- 10 3. An expansible breaking device comprising a cylinder and a plunger relatively movable, said cylinder and plunger having diametrically arranged pressure-exerting surfaces adapted to act on opposing walls of an incision in a mine vein, means for directing a fluid pressure medium into said cylinder, means for limiting the movements of said plunger relatively to said cylinder, and a pulling spring enclosed by said cylinder and plunger for restoring them to relative retracted positions.
4. The combination with a kerf-cutter adapted to cut an upright kerf in a mine vein, of an expansible dislodging device comprising a cylinder and a plunger mounted on said kerf-cutter to move bodily therewith into the kerf cut thereby but operable independently of the feed of the kerf-cutter, means for directing a fluid pressure medium into said cylinder, means for holding said dislodging device in an opening in said kerf-cutter for limited bodily rectilinear movement relatively to the latter at right angles to the kerf walls with the outer surface of the plunger bearing against one wall of the kerf and the inner surface of the plunger bearing against the other wall of the kerf, and means for controlling the expansion of the plunger from the cylinder so as to act without substantial strain on the kerf-cutter but independently thereof.
5. The combination with a kerf-cutter comprising a frame, of a breaking device comprising a cylinder and a plunger mounted on said frame, means for operating said breaking device, a spring connected between the bottom of the plunger and the bottom of said cylinder for automatically restoring said breaking device to its initial position relative to said kerf-cutter upon discontinuance of the operation of said breaking device, and means operable by turning the plunger relatively to said cylinder to release the spring connection between said plunger and cylinder and permit detachment of the plunger.
6. A fluid-pressure-exerting device adapted to be inserted into a kerf in a mine wall, comprising a cylinder and a plunger with a pulling restoring spring enclosed thereby, said spring being connected at its ends to said cylinder and plunger to collapse the latter when the pressure medium within is released, the connection at one end of said spring being detachable, and means on the plunger to receive a spanner wrench to turn

the plunger relatively to the cylinder to release the detachable end of said spring to enable withdrawal of the plunger from the cylinder.

7. In a breaking device, the combination with a cylinder, of a plunger therein, a spring having one end connected to said cylinder and the other end to said plunger and entirely enclosed by said cylinder and plunger, and means for securing the ends of said spring to said cylinder and plunger, said means being inaccessible through either the plunger or the cylinder.

8. In a breaking device, the combination with a cylinder, of a spring having one end secured to the interior bottom of said cylinder, a plunger, and a detachable connection between the other end of said spring and the inner wall of said plunger without any extension through the plunger.

9. In a breaking device, the combination with two relatively movable members, of a spring enclosed by said members, a permanent connection between one end of said spring and one of said members, and latch mechanism between the other end of said spring and the other of said members adapted to be released by the relative turning of said members.

10. An expansible breaking device adapted to be inserted into a kerf in a mine wall and comprising relatively movable members each imperforate throughout, a restoring spring entirely enclosed within said expansible breaking device, and connections between the ends of said spring and said members tending to pull the same together to initial position.

11. An expansible hydraulic breaker adapted to be inserted into a kerf in a mine wall and comprising a shallow cylinder, an imperforate plunger in said cylinder and movable relatively thereto, a spring within said cylinder and having one end connected thereto, and a detachable connection between the other end of said spring in the inner side of said plunger.

12. An expansible hydrostatic breaking device comprising a cylinder and a plunger, a spring within said cylinder and having one end secured thereto, latch mechanism between the other end of said spring and the inner side of said plunger, said latch mechanism securing said plunger to said spring when the plunger is turned from one predetermined position to another predetermined position, and means for preventing the plunger from turning away from the last-named position to effect locking of the latch mechanism.

13. An expansible breaking device comprising relatively movable members, a pulling spring within the breaking device for restoring the parts thereof to initial position, a detachable connection between one end of

5 said spring and one of said members, said connection being detachable by turning one member relatively to the other, and a key on one member extending into a slot in the other member to prevent relative turning of the members to hold the detachable end of said spring locked to the members to which it is connected.

10 14. An expansible breaking device adapted to be inserted into an incision in a mine wall and comprising a cylinder, an imperforate plunger, a pulling restoring spring secured at one end to the inner bottom of said cylinder, and a detachable connection between the 15 other end of said spring and the inner wall of said plunger without accessibility from the exterior of the breaking device through the material of said plunger.

15 16. The combination with a kerf-cutter comprising a flat frame and an endless cutter-chain on the periphery thereof, of a hydrostatically expanding device carried by said flat frame within the boundary of said cutter-chain, a pulling restoring spring connected at its ends to the interior oppositely movable walls of said hydrostatically expanding device, means for directing a pressure medium into said device to expand the same against the action of said spring, and means for controlling the flow of the pressure medium to effect expansion of the device to a limited extent when it is to act as a spacer to prevent binding of the kerf-cutter in the kerf and to also cause said device to expand 30 to a greater extent to break down material adjacent the kerf.

20 17. In a breaking device, the combination with a cylinder, of a spring adapted to be located within said cylinder, means securing one end of said spring to the bottom of said cylinder, a plunger movable in said cylinder, spaced-apart keepers with a slot between them on the inner wall of said plunger, and a transverse extension on one end of said 45 spring adapted to fit in said slot in position for said keepers to move over the same to detachably secure the plunger to said spring.

25 18. A breaking device adapted to be inserted into a kerf in a mine wall and comprising a cylinder and a plunger, an enclosed spring having one end connected to the cylinder, a connection effected between the other end of said spring and the inner wall of said plunger by the turning of the latter relatively to the cylinder, means on the plunger to receive a turning tool to connect the plunger to said spring, and means for locking the plunger against turning relatively to said cylinder after said plunger has been connected to said spring as aforesaid.

30 19. An expansible breaking device comprising a cylinder and a plunger relatively movable, said cylinder and plunger having pressure exerting surfaces adapted to act on 40 opposing walls of an incision in a mine vein,

means comprising a key and slot between said plunger and said cylinder for preventing relative turning of the plunger and cylinder, and an abutment in position to be engaged by said key for preventing the plunger 70 from moving out of said cylinder.

20 20. An expansible breaking device comprising a cylinder and a plunger, a restoring spring having one end connected to the bottom wall of the cylinder, a detachable connection between the other end of said spring and inner wall of said plunger, means comprising a key and slot for preventing turning of the plunger relative to the cylinder to lock the plunger connected to the 80 spring, and an abutment in position to engage the key to prevent the plunger from moving out of the cylinder.

25 21. An expansible breaking device comprising a cylinder and a plunger, a pulling restoring spring enclosed by the cylinder and plunger, a detachable connection between one end of said pulling spring and the inner wall of the bottom of the cylinder, a detachable connection between the other end of said spring and the inner wall of said plunger, said last-named detachable connection being releasable by turning the whole plunger relatively to the cylinder, and means for preventing turning of the plunger relatively to 90 the cylinder to lock the plunger connected to said spring.

30 22. In a mining machine, the combination with a kerf-cutter comprising a cutter frame and an endless cutter chain mounted thereon, of an expansible pressure-exerting device adapted to move therewith into the kerf cut by said kerf-cutter, said pressure-exerting device comprising telescoping cup-shaped pressure-exerting plungers movable in opposite directions each relatively to said cutter frame transversely thereof, and a spring between said plungers, means for operating said kerf-cutter including feed thereof while moving said pressure-exerting device along the kerf cut by said kerf-cutter, a source of fluid pressure supply for said pressure-exerting device, and a valve for the connection between said source and said device to control the operation of the latter.

35 In testimony whereof I have signed my name to this specification on this 8th day of June, A. D. 1929.

40 OLIVE EUGENIE MORGAN,
Executrix of the Estate of Edmund C. Morgan, Deceased.
